UNITED STATES PATENT OFFICE.

DANIEL C. SMITH, OF MILFORD, CONNECTICUT.

REFRIGERATING DEVICE.

Application filed August 19, 1922. Serial No. 582,864.

To all whom it may concern:

Be it known that DANIEL C. SMITH, a citizen of the United States, and resident of Milford, in the county of New Haven and State of Connecticut, has invented certain new and useful Improvements in Refrigerating Devices, of which the following is a specification.

This invention relates to new and useful improvements in artificial refrigerating apparatuses.

The purpose of the invention is to improve upon apparatuses of the above character by providing means for more thoroughly circulating the liquid used therein, and particularly to provide an improved form of generator and absorber wherein a more thorough circulation of the liquid is obtained when passing therethrough and further to simplify and cheapen the construction of a refrigerating apparatus of this class whereby not only improved and more economical results are obtained, but which refrigerating apparatus can itself be constructed at a relatively small cost making it more readily available for domestic uses.

This invention is obviously particularly applicable to a still for distilling gas, such as ammonia, from a suitable liquor, or to an absorber for re-absorbing the expanded gas, after refrigeration has taken place, back into the liquor, and in the accompanying drawings I have shown a form of generator together with a receiver and refrigerator such as my invention may be applied to, yet it will be obvious that its use is not limited to the particular construction and arrangement shown. The generator referred to is used at one time as a still and at another time as an absorber, the gas being of course all extracted from the water in the generator before said water is again used to absorb the returning gas.

A further object of the invention is to control the flow of gas from the receiver to the cooling coils and absorber, so that said gas may be fed forward in such proportions as the absorber is able to receive it.

With these and other objects in view the invention resides and consists in the construction and novel combination and arrangement of parts hereinafter more fully described, illustrated in the accompanying drawings, and pointed out in the claim hereto appended, it being understood that

various changes in the form, proportion, size and minor details of construction within the scope of the claim may be resorted to without departure from the spirit of the invention.

Similar characters of reference denote like or corresponding parts throughout the accompanying drawings, forming a part of this specification, and wherein the generator and other parts are shown operatively connected to form a complete refrigerating apparatus fitted with my improvements.

Fig. 1 shows a vertical sectional end view of my improved refrigerating apparatus as shown on line 1-1 of Fig. 2, and

Fig. 2 shows a longitudinal sectional elevation of the complete apparatus, the section being taken on the irregular line 2-2 of Fig. 1.

Referring in detail to the drawings and the reference characters marked thereon, 5 will be seen to represent the combined generator and absorber which is filled with a suitable solution, such as aqua ammonia, to substantially the level shown at α and in this connection I may say that the solution as used in the operation includes approximately 26% of ammonia gas and 74% of water.

6 represents the storage receiver for holding the distilled products from the generator 5 and as will be seen is connected therewith by pipe 7 having connected therein a condenser 8 of any approved construction. This connecting pipe is further provided with a valve 9 whereby the passage of fluid from the generator through the condenser may be opened or closed and the supply of ammonia taking from the top of the chamber may be controlled. The condenser includes an inlet pipe 10 and an outlet 11, by means of which the supply of cooling water may be drawn off at any time. Both of these pipes 10 and 11 are provided with valves to regulate the passage of liquid therethrough. A gauge 12 is located in the forward end portion of the pipe connection 7 next adjacent to the top portion of the generator.

The lower portion of the receiver is connected by means of a pipe 13 with the cooling coil or heat abstractor 14 for abstracting heat from the atmosphere and positioned at any desired or distant point, the flow of liquid to said coil being controlled by means of valves 15 and 15'. In practice only one of these valves is designed to be

open at a time, in a way to introduce the liquid to the refrigerator in charges, so to speak, of a pound or two at a time, so that the liquid may be used more economically and so that the refrigerator may be maintained at a more uniform temperature. A return pipe 16 connected with another portion of the cooling coil is also provided with a valve 17 to control the return of gas from the refrigerator to the generator 5. The discharge end portion 18 of this pipe is arranged horizontally within the lower central portion of the generator, and is provided with a series of small holes 19 whereby the gas from the pipe is permitted to escape into the chamber and mix with the liquid contained therein.

The lower portion of the chamber is provided with a series of longitudinally disposed partitions 20, 21 and 22 which are connected to the end and side walls of the generator so as to divide said lower portion into compartments 23, 24 and 25, each of smaller dimensions than that of the remaining upper portion 26 of the generator. Each of these three partitions is provided with a series of holes 27 along one of its edge portions, said holes being alternately arranged first in one edge portion of the lower partition, then in the oppositely positioned edge portion of the next partition, and again in the return edge portion of the third partition. The holes in the second partition are thus positioned distant from the holes of the first partition, and the holes of the third positioned on the opposite side of the generator from that of the second and substantially above that of the first partition, thus causing the liquid, having the gas discharged through the holes 19 of the portion 18 of the return pipe absorbed therein, to be circulated horizontally first through the lower compartment 23, see arrows Fig. 1, through the hole 27, and then across through the compartment 24 to the holes 27 in the opposite edge portion of the middle partition, and then back again through the compartment 21 to the holes in the top partition where it enters the larger chamber 26. The absorption takes place when the liquor in the tank 5 is cooled, the same being allowed to stand in a cool place for a sufficient length of time after heating. If desired, a cooling water jacket could be employed for this purpose, as is well known. The circulation of the liquor takes place more particularly during the reheating of the liquor in the generator and absorber and whereby the gas is again discharged from the liquor and conveyed to the receiver.

The heating of the liquid within the generator is accomplished by the use of a longitudinally disposed burner 28, that is arranged beneath and central of the generator, and includes a series of holes for the distribu-

tion of fuel and whereby the lighted flames thereof are applied directly to the underside of the generator to heat the liquor therein. The large horizontal area of the superimposed chambers of relatively small depth allows of very efficient and rapid heating, without the use of coils, so that a simple heating element beneath the tank may be employed.

In practice I find it requires about three-quarters of an hour to discharge all the ammonia gas from the water, which latter always remains in the generator. This gas which is in the form of hot vapor passes away through the pipe 7 when the valve 9 is open, the flow of gas being of course regulated by said valve, which is open when the heat is on and closed when the heat is turned off.

When all the ammonia gas has been discharged from the generator and the heat and the water turned off, the generator is allowed to cool down and is then ready to begin the re-absorption of the gas from the refrigerator.

The water remaining in the generator after distillation will permit the re-absorption of every ounce of ammonia gas that it originally contained and will then be ready for discharging. This distilled product is capable of absorbing the usual amount of heat from the atmosphere which in turn lowers the temperature of the surrounding atmosphere, but when one pound of this distilled product has absorbed its given heat quantity it can do no more for the present and must be again subjected to the action of heat in the generator and condensation in the condenser, when it will again possess power of absorbing the heat from the surrounding atmosphere. This cycle may be repeated indefinitely without loss in effect providing the apparatus is properly sealed from the air.

The operation of the apparatus would first of course include the filling of the generator with a solution of ammonia of the character specified after which heat would be applied to the under side of the generator from the gas burner shown, the effect of which is to heat the liquid and separate the ammonia gas from the water. From the foregoing it will be seen that the gas thus extracted from the generator assumes the level indicated by 5 and is then transferred to the receiver for use in the refrigerator. By opening the valve 15, a sufficient quantity of liquid ammonia denoted C may be admitted from the receiver to the heat abstracter 14, there to absorb heat from the atmosphere in order that refrigeration may be produced, as is well known. The resulting ammonia gas is caused to return to the generator in the manner already described.

Having thus described my invention what

I claim and desire to secure by Letters Patent is: —

In a refrigerating apparatus, in combination a condenser and receiver adapted to contain liquid ammonia, a heat abstracting element connected to the receiver and adapted to receive liquid ammonia therefrom, said liquid ammonia becoming gaseous in said element as it absorbs heat from the atmosphere, an absorber and generator adapted to contain aqua ammonia and consisting of a relatively long horizontally disposed tank and longitudinally extending vertically spaced horizontal partitions disposed in the lower portion of said tank to form longitudinally disposed superimposed chambers, each of said partitions having openings adjacent one edge portion, the openings of each partition being opposite the openings of the adjacent partitions to insure flow of liquid through the generator passing horizontally through the chambers in relatively large area superimposed layers, a pipe connections between said heat abstracting element and said absorber and generator, said pipe connection having a perforated lower end situated in the lowermost of said chambers, a shut-off valve in said pipe between the perforated end and said element, means for heating said absorber and generator at its lower portion, whereby a thermo-flow of the liquor is produced upwardly and horizontally through said chambers and ammonia gas is given off at the top, and a connection between the upper portion of said absorber and generator and said condenser and receiver.

Signed at Bridgeport, in the county of Fairfield and State of Connecticut, this 11th day of March, A. D. 1922.

DANIEL C. SMITH.
